(57) **CLAIM**
The ornamental design for a switch plate assembly, as shown and described.

DESCRIPTION

This application contains at least one photograph executed in color. Copies of this application publication with color photographs will be provided by the Office upon request and payment of the necessary fee.

FIG. 1 is an exploded front perspective view of a first embodiment of a switch plate assembly showing our new design; FIG. 2 is a front view thereof shown in an assembled condition;

FIG. 3 is a back view thereof;

FIG. 4 is a left perspective view thereof, the right perspective view being a mirror image thereof;

FIG. 5 is a left side view thereof, the right side view being a mirror image thereof;

FIG. 6 is a bottom view thereof, the top view being a mirror image thereof;

FIG. 7 is an exploded front perspective view of a second embodiment of a switch plate assembly showing our new design;

FIG. 8 is a front view thereof shown in an assembled condition;

FIG. 9 is a back view thereof;

FIG. 10 is a left perspective view thereof, the right perspective view being a mirror image thereof;

FIG. 11 is a left side view thereof, the right side view being a mirror image thereof; and,

FIG. 12 is a bottom view thereof, the top view being a mirror image thereof.
